(57) **CLAIM**

The ornamental design for a display screen or portion thereof with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a first image of a display screen or portion thereof with animated graphical user interface showing our new design; and,

FIG. 2 shows a second image thereof.

The peripheral dashed broken lines depict a display screen or portion thereof and form no part of the claimed design. The appearance of the graphical user interface sequentially transitions between the images shown in FIGS. 1-2. The process or period in which one image transitions to another forms no part of the claimed design.
